PATENTED FEB. 5, 1806.

657X

C. THOMPSON.
DELINEATING MACHINE.

Cephus Thompson

Feb 5, 1806

Seller's Patent. - Filed Feb. 5, 1806.

The schedule referred to in this Seller's Patent and making part of the same containing a description in the words of the said Cephus Thompson himself of his delineating machine for copying charts, Landscapes, paintings, profiles, &c. -

This machine in its principles and operation may be said to resemble the Eye or Camera Obscura. The several parts of light which are supposed to depict the image of objects on the Retina are represented by a pencil of wood with a point at each end, in the place of the camera is an universal joint, through which is fixed the artificial pencil. Like the image on the Retina the drawings effected by this machine are inverted copies of the originals. The delineator may be used to great advantage by engravers, and painters in taking the outlines of the painting intended to be copied upon the Plate, Canvas, or Paper. It may be used in taking profiles likewise; in tracing charts & pictures; in copying Landmarks, Buildings, &c. &c. exactly from nature, and all at such sizes as the pleasure of the artist may require.
